Primary Examiner — T Chase Nelson*Assistant Examiner* — Jonathan J. Han(74) *Attorney, Agent, or Firm* — Shook, Hardy and Bacon L.P.(57) **CLAIM**

The ornamental design for a shoe, as shown and described.

DESCRIPTION

FIG. 1 is a first side rear perspective view of a shoe showing my new design;

FIG. 2 is a second side rear perspective view thereof; and, FIG. 3 is a second side view thereof.

The even-length broken lines are directed to environment, represent unclaimed subject matter, and form no part of the claimed design.

The long-and-short broken lines immediately adjacent shaded areas form an unclaimed boundary, and form no part of the claim.
